UNITED STATES PATENT OFFICE.

GUY W. CAMPBELL, OF SAN JOSÉ, CALIFORNIA, ASSIGNOR OF ONE-HALF
TO THE SAN JOSÉ AGRICULTURAL WORKS, OF SAME PLACE.

ORCHARD AND VINEYARD CULTIVATOR.

SPECIFICATION forming part of Letters Patent No. 387,765, dated August 14, 1883.

Application filed April 28, 1883. Serial No. 272,175. (No model.)

To all whom it may concern:

Be it known that I, GUY WARD CAMPBELL, of San José, Santa Clara county, State of California, have invented an Improvement in Orchard and Vineyard Cultivators; and I hereby declare the following to be a full, clear, and exact description of the same.

My invention relates to that class of cultivators specially adapted for use in orchards and vineyards; and my invention consists in a shifting or adjustable tongue or pole, its arrangement and mechanism for operating it; in an adjustable seat and its arrangement; in attachable and detachable side teeth and the manner of connecting and disconnecting them; in the novel construction and arrangement of the frame; in the peculiar hub or dust cap or cover and scraper-support, and in details of construction, all of which, together with the objects of the several improvements, I shall hereinafter fully describe by reference to the accompanying drawings, in which—

Figure 1 is a perspective view of my cultivator. Fig. 2 is a horizontal section of the hub or dust cap or cover, showing its application to the wheel-hub and its support of the scraper. Fig. 3 is a vertical longitudinal section through the front cross-plate, a' , of the frame, showing the pivoting of brackets B.

A is the frame generally. This consists of longitudinal parallel body-bars a , the double cross-plates a' , between which the rear ends of bars a are bolted, and the parallel back bars, a^2 , lying outside of the planes of the body-bars and within the planes of the ends of the cross-plates. The body-bars and the back bars are made of channel-iron. The bars a are connected about their centers by the cross-plate a^3 and near their forward ends by the double cross-plates a^4 . To the upper one of these cross-plates a^4 is pivoted by the pin or bolt b the bracket B, in which the pole or tongue C is connected by the cross-bolt c . The tongue extends rearwardly to the back of the frame, and has pivoted on its extreme rear end the lever D, the lower end of which is forked and bears against the fixed fulcrum-pin d , extending from the lower cross-plate, a' .

E is a rack, which is fixed on top of the rear end of the tongue or pole and with which the lever D engages. On the upper cross-

plate, a' , is fixed a guide-rail, F, in which a bent guide-arm, c' , on the tongue or pole C plays. It will now be seen that by moving the lever D it swings or shifts the tongue or pole about the pivot b to one side or the other. The object of this is to get the horses away from the vines and trees and still allow the machine to work up as close to them as possible. Another advantage of this shifting or swinging tongue is that when the machine is working on the hillside the tendency to work downhill may be counteracted by throwing the tongue to one side, so as to direct the wheels slightly against the slope of the hill.

65

G are the wheels of the machine connected with the main frame in any suitable manner.

H is a bracket firmly secured on the tongue or pole over the axial center of the machine. The top of this bracket is provided with a longitudinal slot, g , in which plays the threaded pin h on the spring-support h' of the seat h^2 . A thumb-nut, h^3 , is fitted on the threaded pin and serves to hold the seat in the position to which it is set. This construction enables the seat H to be set forward or back to one side or the other of the axial center of the machine, the object being to transfer the weight backwardly upon the teeth when the machine is at work and forwardly when not at work.

75

I are the ordinary teeth of the cultivator, having suitable standards secured to the frame.

J are supplementary side teeth to be attached to the frame when the width of the machine is to be increased, according to the work desired, whether in orchard or in vineyard. These teeth J have outwardly-extended bent standards j , and they are secured to the frame by passing into a grooved casting, K, which is bolted between the ends of the cross-plates a' of the main frame, and said standards are secured in this position by means of set-screws k . These castings hold these teeth firmly and provide for their ready removal or replacement by taking out or putting in the set-screws. By these removable teeth the machine may be adapted for wider work, according to the place in which it is used and to the necessities of the case, thus rendering the machine practical in both orchard and vineyard.

90

95

L is a casting, one end of which is socketed and fixed over the inner end of the hub of the

wheel; the other end is extended, and to it is bolted the lower end of the wheel-scraper N. This casting therefor forms a combined dust cover or cap for the hub and support for the 5 scraper.

The arrangement of the frame, as described, is of a simple nature, and yet of a character enabling the teeth to be set in the proper positions for working.

10 Having thus described my invention, what I claim as new, and desire to secure by Letters Patent, is—

15 1. In an orchard and vineyard cultivator, the combination of the frame and the supplementary teeth having bent standards extended to one side and adapted to be fitted into and detachably secured to the frame, whereby the width of the machine is varied, substantially as herein described.

20 2. In an orchard and vineyard cultivator, the frame having the fixed teeth, in combination with the independent or supplementary teeth having shanks adapted to be fitted into and detachably secured to the sides of the 25 frame to vary the width of the machine, substantially as herein described.

25 3. In an orchard and vineyard cultivator, the cross-plates of the frame having the grooved castings bolted between their ends, in 30 combination with the supplementary attachable and detachable teeth having shanks fitted to the grooved castings, and the set-screws for

holding said shanks, substantially as herein described.

4. In an orchard and vineyard cultivator, 35 the main frame, consisting of the parallel longitudinal body-bars, the cross-plates, between which the rear ends of the body-bars are bolted, and the parallel back bars bolted to the cross-plates outside of the planes of the body-bars 40 and within the planes of the ends of the cross-plates, substantially as herein described.

5. In an orchard and vineyard cultivator, the main frame consisting of the parallel longitudinal body-bars, the cross-plates connecting their forward ends, and cross-plates connecting their centers, the cross-plates, between which the rear ends of the body-bars are bolted, and the parallel back bars bolted to said cross-plates outside of the planes of the body-bars 50 and within the planes of the ends of said cross-plates, substantially as herein described.

6. In an orchard and vineyard cultivator, the single casting serving as a hub or dust cap or cover for the wheel and as a support 55 for the wheel-scraper, substantially as herein described.

In witness whereof I have hereunto set my hand.

GUY W. CAMPBELL.
